[57] **CLAIM**

The ornamental design for a fringed belt, as shown and
described.

DESCRIPTION

FIG. 1 is a front perspective view of a fringed belt showing
our new design;

FIG. 2 is a front elevational view thereof in an unfastened
position;

FIG. 3 is a top plan view thereof;

FIG. 4 is a rear elevational view thereof;

FIG. 5 is a bottom plan view thereof;

FIG. 6 is a right end elevational view thereof; and,

FIG. 7 is a left end elevational view thereof.

The dashed lines represent conventional stitching in FIGS.
1, 2, and 4.
